UNITED STATES PATENT OFFICE.

CHARLES F. FREDE, OF ST. LOUIS, MISSOURI, ASSIGNOR TO COMMONWEALTH STEEL COMPANY, OF GRANITE CITY, ILLINOIS, A CORPORATION OF NEW JERSEY.

CAR UNDERFRAME.

Application filed February 21, 1927. Serial No. 169,926.

My invention relates to railway rolling stock and consists in an improved railway underframe construction.

The object of my invention is to provide a railway underframe consisting entirely, or in a large part, of a single member, and preferably of a casting in which extensive normally flat surfaces are corrugated as more particularly described below. Such corrugation is for the purpose of strengthening or reinforcing relatively thin plate-like members so as to facilitate the making of the latter, particularly if they are cast, and so as to reinforce and strengthen the sills and transverse members of the underframe.

In one form, my invention is adapted to form a portion of a tank such as a tender tank, and it is a further object of my invention to produce a tank underframe casting in which the plate-like portions of the underframe are corrugated and serve as a portion of the tank.

In the accompanying drawings which illustrate my invention,—

Figure 1 is a top view of one-half of one side and one end of a tender underframe and tank bottom embodying my invention.

Figure 2 is a vertical longitudinal section taken on line 2—2 of Figure 1.

Figure 3 is a transverse vertical section taken on line 3—3 of Figure 1.

Figures 4, 5 and 6 are corresponding views and sections illustrating a different type of underframe adapted to be used for ordinary freight cars or passenger cars or electric locomotives or other railway vehicles where the integral formation of the floor and the underframe sills, etc., may be advantageous.

The underframe illustrated in Figures 1, 2 and 3 is shown as consisting of a one-piece casting containing the usual center sills 1, the ends of which form draft sills 2. The casting also includes side sills 3, end sills 4, and transverse sills or transom-like members 5 and 6, members 5 being indicated as bolsters through which the underframe is supported upon the truck. The side sill and end sills are provided with suitable pads to which the superstructure plates P may be welded or riveted.

Integral with the sills referred to above is a horizontal wall or plate 7 extending between the sills and imperforate throughout

length and width so as to form a liquid-tight bottom for the vehicle. This wall 7 is shown as being provided with a plurality of corrugations which may be disposed in any desired arrangement as is best adapted for meeting the various stresses which may be imposed upon the casting in the manufacture thereof or in its use after the vehicle is completed. For example, the corrugations 8 at the left hand of Figure 1 are shown as extending longitudinally of the underframe and parallel with the sills 1 and 3 and transversely of the end sill 4 and the bolster 5. Corrugations 9 in the intermediate portion of the underframe are shown as extending at right angles to corrugations 8 and parallel with transom members 5 and 6 but terminating short of center sill 1 and side sill 3. The corrugations 10 in the middle portion of the underframe are shown as being arcuate or circular and are disposed about a common center C.

Suitable reinforcing ribs 11 are provided to brace wall 7, and the ribs may be arranged transversely of or parallel with the corrugations as desired. The transom elements 5 and 6 are provided with suitable openings 12 which lighten the casting and permit the free passage of liquid from one end of the casting to the other.

It will be understood that the underframe is adapted to carry floor beams, flooring and other superstructure on the sills and transoms in the same manner as any ordinary underframe and in addition the full depth of the underframe is available for use as a storage compartment for liquids.

The provision of the corrugations 8, 9, and 10 in the bottom wall of the casting relieves shrinkage strains in the casting as it cools after pouring, and also assists in maintaining a uniform thickness of the wall. This is due to the tendency of the corrugations to straighten out when they are placed under tension whereby no part of the fluid metal in the wall is drawn away from another part.

In the modification illustrated in Figures 4, 5 and 6 the plate-like member 13 is located at the level of the top faces of the sills 14, 15 and 16 and bolsters 17 and intermediate transoms 18 but is formed integrally therewith and is corrugated substantially throughout its area similar to the wall

7 of Figures 1, 2 and 3. The wall 13 is suitably reinforced intermediate the sills and transoms by ribs 20. In this structure, I also illustrate the formation of corrugations 5 19 intermediate the center sills 14 which may be desirable.

Composition flooring can be applied directly to the underframe without finishing the latter and without the addition of other 10 elements, and the composition flooring will fill the depressions in the plate and produce a level upper surface.

Obviously other variations in my invention may be made, and I contemplate the 15 exclusive use of the subject-matter of my invention as expressed in my claims irrespective of modifications in the arrangement of the corrugations or variations in the other details of the underframe.

20 I claim:

1. In an underframe for a railway vehicle, longitudinal and transverse sills, and a corrugated horizontal wall extending between said sills and formed integrally therewith.

25 2. In an underframe for a railway vehicle, longitudinal and transverse sills provided with surfaces adapted to mount tank superstructure, and a corrugated horizontal wall between said sills adapted to form the bottom of a tank structure.

3. In an underframe for a railway tank vehicle, a corrugated horizontal plate forming the bottom of the tank structure.

35 4. In a cast underframe, center sills, bolsters, and a corrugated horizontal wall connecting the lower edges of said sills and bolsters and forming therewith the lower portion of a tank structure.

40 5. In a cast underframe for a railway tank vehicle, a longitudinal sill, and a plate forming a tank bottom with corrugations extending parallel with said sill.

45 6. In a cast underframe for a railway tank vehicle, a transverse transom or like member, and a plate forming a tank bottom with corrugations extending parallel with said transom.

50 7. In a cast underframe for a railway tank vehicle, longitudinal sills, transverse transom-like members, and a plate forming a tank bottom between said sills and members and provided with arcuate corrugations.

55 8. In a cast underframe for a railway tank vehicle, longitudinal sills, transverse transom-like members, and a plate forming a tank bottom between said sills and members and provided with a plurality of corruga-

tions, the corrugations in different portions extending in different directions.

9. In a cast underframe for a railway tank 60 vehicle, a horizontal plate forming a tank wall and having a series of parallel corrugations, and an upstanding reinforcing rib extending across said corrugations intermediate their ends.

65 10. In a cast underframe for a railway tank vehicle, a horizontal plate forming a tank wall and having a series of parallel corrugations, and an upstanding rib extending parallel with said corrugations along one 70 of the latter.

75 11. In a cast underframe for a railway tank vehicle, a horizontal plate forming a tank wall and having a series of concentric arcuate corrugations, and an upstanding reinforcing rib extending across said corrugations.

80 12. In a locomotive tender, a tank having a corrugated bottom forming a part of the tender underframe.

85 13. In a locomotive tender, a tank having a bottom plate consisting of a corrugated casting forming part of the tender underframe.

90 14. In a cast underframe for a railway vehicle, longitudinal and transverse sills and transoms, a corrugated horizontal wall extending between said sills and transoms, and a reinforcing rib extending across the corrugations of said wall intermediate said sills and transoms.

95 15. In a cast underframe for a railway vehicle, spaced sills, a horizontal plate extending between said sills and having a series of parallel corrugations, and a reinforcing rib extending between said sills and parallel with said corrugations.

100 16. In an underframe for a railway vehicle, spaced longitudinal sills, and a corrugated horizontal wall extending between said sills and formed integrally therewith.

105 17. In an underframe for a railway vehicle, center sills, and a corrugated horizontal wall extending between said sills and formed integrally therewith.

110 18. In an underframe for a railway vehicle, center sills, side sills, and a corrugated horizontal wall extending between adjacent side sills and center sills and formed integrally therewith.

In testimony whereof I hereunto affix my signature this 12th day of Feb., 1927.

CHARLES F. FREDE.
